UNITED STATES PATENT OFFICE.

JOSEPH N. PAPENDRY, OF EAST LIVERPOOL, OHIO.

ARMOR-PLATE.

1,014,510.

Specification of Letters Patent.

Patented Jan. 9, 1912.

Application filed May 18, 1911. Serial No. 627,070.

To all whom it may concern:

Be it known that I, JOSEPH N. PAPENDRY, a citizen of the United States, residing at East Liverpool, in the county of Columbiana and State of Ohio, have invented new and useful Improvements in Armor-Plates, of which the following is a specification.

This invention relates to armor plate, and has particular application to certain novel and useful improvements in defensive armor for war vessels and fortifications.

In carrying out my invention, it is my purpose to provide an armor designed to form an effective protection against projectiles, by receiving the concussions and shocks due to the striking of such projectiles.

Still a further object of my invention is to provide a protective armor composed of a series of elements so combined and assembled that the greatest possible effectiveness is obtained.

It is my purpose to provide an armor of the type described which may be readily applied to war vessels or forts and which will be capable of effectively absorbing the shocks occasioned by the striking of the projectiles, thereby protecting not only persons commanding the ships or fortifications, but also affording a means for protecting expensive armor and equipment.

With the above recited objects and others of a similar nature in view, the invention consists in the construction, combination and arrangement of parts falling within and forming a part of the appended claims.

In the accompanying drawing:—Figure 1 is a horizontal sectional view taken through a portion of a wall, such as the side of a war vessel or fortification, and showing my improved armor applied thereto. Fig. 2 is a vertical sectional view taken through the armor. Fig. 3 is a detail view of the sleeve plate for the plunger rods.

Referring now to the accompanying drawing in detail, the letter A indicates the side of a war vessel or the like, to which my improved armor is designed to be applied. The body of the armor plate itself comprises a backing 1 formed of a mesh or netting of relatively strong, thick, wire or cables, said wire or cables being woven to any desired pattern. Applied to the face of this wire mesh is a series of metallic armor plates 2, in the present instance six in number, and composed of any suitable armor plate, such as Harveyized steel, Krupp armor, or the

like. These plates are placed face-to-face one upon the other.

The numeral 3 indicates the facing of my improved armor plate which is composed of 60 layers of relatively thick rubber, and between this outer rubber body 3 and the steel plate, I interpose a plurality of relatively heavy, strong, powerful coil springs 4, one end of each of said springs bearing against 65 the steel plates, as at 5, while the opposite end of said spring bears against the rubber plate or body as at 6. It is, of course, understood that I may employ any suitable number of these coil springs, dependent 70 upon the class and thickness of the armor.

Secured to the inner face of the side of the vessel or wall of the fortification, are a number of air cylinders 7 which are riveted or otherwise secured to said wall or side so as 75 to be retained in position. Within each cylinder moves a plunger 8, each plunger being connected to a relatively long, thick, powerful shaft or rod 9, one end of which is secured as at 10 to the plunger, said rod projecting through a bore 11 in the cylinder, thence through a bore 12 in the side of the vessel or fort, and thence through passages or bores 13 and 14 in the steel plates and rubber body, respectively, the ends of said 80 rods being provided with enlarged heads 15 at the facing of the rubber body. Secured to each rod, at the point where it passes through the metallic mesh is a stop composed of two plate sections 16, each provided 85 with a semi-cylindrical member 17, said semi-cylindrical sections forming a split sleeve, adapted when the parts are assembled to fit over the rod and to be secured thereto by bolts as at 18. Interposed between the plates 16 and the air or cushion cylinders are relatively powerful coil springs 19, each of said springs encircling one of the plunger rods.

From the above description, taken in connection with the accompanying drawing, the construction and manner of assembling and use of my improved armor will be readily apparent.

In assembling the armor, the cylinders are 105 secured to the inside of a wall or vessel with the plungers properly placed therein and the rods projected through the passages or bores in such side. The springs 19 are now placed in position between the cylinders and 110 the plates and the remaining portions of the rods or shafts projected through the open-

ings in the wire mesh, steel and rubber, as shown in the drawing, the ends of the rods projecting through the rubber facing or body being then upset or headed so as to retain all the parts in their combined or removed position.

It will be seen that I have provided an exceedingly strong, durable, efficient and effective form of armor plate, which may be 10 used wherever it is desired to install protection against projectiles, and while I have herein shown and described one particular embodiment of my invention by way of illustration, I wish it to be understood that 15 I do not confine myself to all the precise details of construction herein set forth, as modification and variation may be made without departing from the spirit of the invention or exceeding the scope of the appended claims.

Having thus described the invention, I claim:—

1. In an armor plate, the combination of an outer body of resilient material, a plurality of metallic armor plates, flexible means interposed between the armor plates and resilient material, a metallic mesh adjacent to the armor plates, and pneumatic means for cushioning the armor.

2. In an armor, the combination of a body 30 of rubber, steel armor plate, springs interposed between the armor plate and the rubber, a facing of woven wire for the metallic armor plate, a plurality of air cylinders connected to the structure to be protected, and 35 plungers moving in said cylinders and engaging with the rubber, steel plates and mesh.

3. In an armor, an armor plate comprising a facing of resilient material, a plurality of metallic armor plates arranged face-to-face, a body of woven wire in contact with the armor plate, springs interposed between the armor plate and body of rubber, air cylinders connected to the structure to be 40 protected, plungers moving in said air cylinders, rods for said plungers projecting through the side of the structure to be protected and through the armor plate formed by the rubber, steel and wire mesh, and 45 springs coiled about said rods between the cylinders and body of armor.

In testimony whereof I affix my signature in presence of two witnesses.

JOSEPH N. PAPENDRY.
